UNITED STATES PATENT OFFICE.

NEWEL P. HANSON, OF WATERVILLE, ASSSIGNOR, BY MESNE ASSIGNMENTS,
TO THE INDURATED FIBRE COMPANY, OF PORTLAND, MAINE.

MACHINE FOR FORMING HOLLOW ARTICLES FROM PULP.

SPECIFICATION forming part of Letters Patent No. 365,743, dated June 28, 1887.

Application filed October 20, 1886. Serial No. 216,700. (No model.)

To all whom it may concern:

Be it known that I, NEWEL P. HANSON, a citizen of the United States, residing at Water-
ville, in the county of Kennebec and State of
5 Maine, have invented certain new and useful
Improvements in Machines for Forming Hol-
low Articles from Pulp; and I do hereby de-
clare the following to be a full, clear, and ex-
act description of the invention, such as will
10 enable others skilled in the art to which it ap-
perts to make and use the same.

My invention relates to machines for form-
ing and pressing articles of wood or paper
pulp, and it is designed particularly as an im-
15 provement to be applied to a machine for
forming hollow articles from wood or paper
pulp patented to Joseph G. Bodge, October
30, 1883, said Letters Patent being numbered
287,614. In the Bodge machine above men-
20 tioned a flexible or elastic diaphragm envel-
oping a previous former was used, the whole
inclosed in a tight case. Pulp was forced in
under pressure between the elastic diaphragm
and the previous former, the diaphragm ex-
25 panded away from the former and the pulp
deposited on its surface, after which a heavy
hydrostatic pressure was applied to the out-
side of the diaphragm, pressing it against the
outside of the formed article. By the use of
30 a diaphragm made up wholly of elastic ma-
terial it was not possible to give to the out-
side of the article any peculiar form differ-
ing from the interior former or core. Neither
would the outside surface of the pulp article
35 be as smooth and even as was desirable. In
the forming of pails, for instance, the corner
around the periphery of the bottom was
rounded off and made thinner, and conse-
quently weaker, than the other portions of
40 the pail, from the fact that the rubber dia-
phragm drew across this corner with consider-
able force, and because the drainage at that
point was less free than elsewhere. In order
to form the chine of the pail a special iron
45 hoop had to be made and put on the pail after
the same was formed, this being done not to
strengthen the bottom, but to provide the de-
sired form. To remedy this difficulty, I put
in the pail-machine a rigid section or head on
50 the inside of the elastic diaphragm and se-

cured thereto, and having around the periph-
ery of its under face a groove, which formed
a mold, into which the pulp was compressed
to form the chine of the pail, the flat portion
of this section forming the pail-bottom. This 55
section is constructed of any suitable rigid
or nearly rigid material, and has a smooth
under surface.

In the drawings, Figure 1 represents a section
through the Bodge pail-machine with my im- 60
provement applied. Fig. 2 illustrates another
manner in which it may be used or applied.

C is the previous former; F, the elastic dia-
phragm; A, the outer dome or case; J, the
pulp-inlet; I, the pipe for admitting water for 65
hydrostatic pressure, and G is the rigid head
secured to the inside of the diaphragm F in
such a position that it will come down and
form the bottom of the pail. The head G has
around the periphery of its under side the 70
groove g, having the reverse shape of the
chine of the pail. As the diaphragm is forced
inward against the pulp the head G comes
down and forms the bottom of the pail, the
pulp being forced into the groove g, thus form- 75
ing the chine of the pail. If care is taken in
having the elastic diaphragm of uniform thick-
ness, the head G will come down into place
each time with little variation, and will not
need a centering device. The smooth and 80
rigid surface of the head G gives to the outer
surface of the pulp a smoothness which it does
not take where it comes in contact with the
flexible rubber, and hence it is desirable to
use such a rigid section whenever possible in 85
forming pulp by this process.

In Fig. 2 is illustrated a machine where a
considerable portion of the diaphragm is made
up of a rigid section, the dotted lines showing
the position taken by the flexible portion of 90
the diaphragm after the outside hydrostatic
pressure is applied. Even when the outside
of the pulp does not need to have a special
form given to it which is different from the
inner surface, it is useful to have this rigid 95
section as large as possible, because that por-
tion formed by this section will have a smooth
surface, requiring but little finishing, whereas
those parts which are formed by the elastic
portion of the diaphragm are quite rough and 100

uneven and require to be worked down by sand-paper or other means to a considerable extent.

5 Pneumatic or hydrostatic pressure may be used equally well on the outside of the diaphragm.

My invention may be applied to a great variety of machines for forming hollow articles.

I claim—

10 In a machine for forming hollow articles from pulp, a previous former on the exterior surface of which the pulp is deposited, an

elastic diaphragm outside of said former and having attached to it a rigid section or head, an exterior dome or case, means for applying hydrostatic or pneumatic pressure outside of 15 said diaphragm, and means for introducing the pulp, substantially as described.

In testimony whereof I affix my signature in presence of two witnesses.

NEWEL P. HANSON.
